LADLE

Robert S. A. Dougherty, Bethlehem, Pa., assignor
to Bethlehem Steel Company, a corporation of
Pennsylvania

Application February 26, 1938, Serial No. 192,696

6 Claims. (Cl. 266—39)

My invention relates to slag pots used for conveying molten slag from a furnace to a slag dump, and particularly to an improved construction of such pots.

5 Slag pots in general are made in the shape of an inverted thimble, with outwardly flaring sides and a rounded bottom. Such pots are generally equipped with a plurality of seats intermediate the top and bottom of the pot by which they may 10 be mounted on a yoke provided with trunnions which provide a pivot on which the slag pot may be tipped while resting on suitable supports on a slag car.

In service, the high temperatures to which slag 15 pots are subjected cause stresses in the walls of the pots and eventually cause the walls to crack and thereafter to deteriorate rapidly.

In addition, these high temperatures cause the 20 walls of the pot to expand, particularly in the region immediately below the supporting yoke. As long as such expansion is not excessive, no 25 harm occurs, but in practice the walls of the pot are frequently strained beyond their elastic limit and acquire a permanent bulge or set. When 30 slag is handled and dumped from such a pot in a molten condition no harm results from the pressure of a bulge in the side walls. However, slag is frequently kept in the pots for a period of several hours and in such case the body of slag 35 in immediate contact with the walls of the pot cools and forms a layer of solidified slag known as a skull. If a skull is formed in a pot, the sides of which are bulged as above described, the constriction of the pot above the bulge prevents the 40 removal of the skull by merely tipping the pot, and it is necessary to break up the skull with sledges or crowbars before it can be removed from the pot.

The object of my invention is to provide a slag 45 pot so constructed that cracking, which causes the pot to deteriorate rapidly, and bulging, which makes the skull difficult to remove, are eliminated.

Other objects of my invention will be apparent 50 from the drawings and from the following description.

In the drawings:

Figure 1 is a top plan view of a slag pot constructed in accordance with my invention;

Fig. 2 is a view partly in vertical elevation 55 and partly in vertical section along the line 2—2 of the slag pot shown in Fig. 1;

Figs. 3 and 4 are views in horizontal section of the slag pot taken along the lines 3—3 and 4—4 of Fig. 2, respectively; and

Fig. 5 is a fragmentary view in vertical sec-

tion of a slag pot along the line 5—5 of Fig. 1 showing a seat which rests upon the yoke.

In the drawings, which show a slag pot of thimble shape, 1 shows the outwardly flaring side wall of generally circular contour, and 2 shows the bottom of the pot which is preferably rounded or spheroidal in shape.

5 In order to accommodate a yoke (not shown) whereby the pot may be mounted on a slag car, the wall 1 is provided with a plurality of seats 3 which 10 rest upon the yoke, and projections 4 which accommodate means for securing the pot to the yoke.

The pot is also provided with eyes 5 whereby the 15 pot may be transferred by means of a crane to and from the slag car.

The wall 1 contains a plurality of inwardly extending corrugations 6 disposed vertically around the circumference of the pot. These corrugations begin at a point 7 somewhat above the bottom of 20 the slag pot and terminate at a point 8 somewhat below the top of the pot. These corrugations preferably increase in depth from their points of beginning 7 and 8 to a maximum at point 9 intermediate the ends, but my invention is not intended to be limited by this feature, since the 25 spirit of my invention will be met by the use of corrugations of equal depth throughout their lengths.

In addition to the inwardly extending corrugations 6, above described, the top of the pot is provided with a plurality of outwardly extending vertical corrugations 10 disposed between the 30 inwardly extending corrugations 6 and having a maximum depth at point 11 on the rim of the 35 pot and terminating at point 12 intermediate the top and the bottom of the pot.

As heretofore stated, slag pots of ordinary design 40 frequently crack in service because of the expansion of the walls of the pot resulting from the intense heat of the molten slag contained in the pot. Moreover, such pots tend to become bellied 45 immediately below the supporting yoke on which the pot is mounted in the slag car, with the results hereinabove described. It will be seen that with my arrangement of corrugation there is provided the greatest number of corrugations at the portion of the pot subject to the highest temperatures.

With a slag pot constructed in accordance with 50 my invention, however, these results do not follow. The inwardly extending corrugations 6 and the outwardly extending corrugations 10 act as stiffening members which reinforce the wall 1 and tend to prevent the bellying of the wall. 55

Moreover, in my preferred construction the corrugations 6 have their maximum depth and consequently their maximum strength at the point where the maximum deformation of the pot usually occurs.

In addition, the corrugations 6 and 10 permit the metal of the pot to expand freely under the influence of the heat of the molten slag and to contract freely when such heat is removed, with the result that cracking of the walls due to stresses set up by such expansion and contraction is prevented or greatly lessened.

Since a pot constructed in accordance with my invention will not belly, no difficulty is found in removing the skull of cooled slag which is formed if the slag is allowed to remain in the pot for a considerable time.

It will be seen moreover that the inwardly extending ribs 6 facilitate the removal of any skull which may be formed on the interior of the pot since by reason of their increasing depth from their point of inception 7 to their point of maximum depth 9 they form bearings upon which the skull is supported as it slides from the pot, and lessen the friction which results from the contact between the skull and the interior wall of the pot.

Having thus described my invention, what I claim and desire to secure by Letters Patent is:

1. A ladle comprising a shell having outwardly flaring side walls, said side walls containing a plurality of inwardly extending corrugations having their greatest depth intermediate the ends thereof, and a plurality of outwardly extending corrugations at the upper end thereof.

2. A ladle comprising an outwardly flaring substantially circular shell, said shell containing

a plurality of inwardly extending substantially vertical corrugations extending from a point near the bottom of the shell to a point below the top of the shell and a plurality of outwardly extending vertical corrugations at the top of the shell.

5

3. A ladle comprising a shell having side walls of inverted frustro-conical shape, said side walls containing a plurality of inwardly extending corrugations intermediate the top and the bottom thereof varying in depth from their ends to points intermediate their ends, and a plurality of outwardly extending corrugations at the top thereof increasing in depth from their lower to their upper ends.

4. A ladle comprising a shell having outwardly flaring side walls containing a plurality of inwardly disposed corrugations extending upwardly to a point below the rim of the shell and a plurality of outwardly disposed corrugations extending upwardly from a point below the rim of the shell to said rim.

5. A ladle having a substantially vertical wall provided with a first series of corrugation extending up the wall from near the bottom of the wall and terminating short of the top of the wall, and a second series of corrugation extending down the wall from near the top of the wall and extending beyond the first series and in intercalated relation therewith.

6. A ladle having a substantially vertical wall provided with a corrugation extending up the wall from near the bottom of the wall and terminating short of the top of the wall, and a second corrugation extending down the wall from near the top thereof to a point beyond the point of termination of the first mentioned corrugation.

ROBERT S. A. DOUGHERTY.
